UNITED STATES PATENT OFFICE.

JOHN PETERS, OF MILAN, ITALY.

METAL WALL FOR BUILDINGS, MASONRY-WORK, AND THE LIKE.

No. 853,261.

Specification of Letters Patent.

Patented May 14, 1907.

Application filed July 2, 1906. Serial No. 324,483.

To all whom it may concern:

Be it known that I, JOHN PETERS, engineer, a subject of the King of Great Britain, and a resident of Milan, Italy, have invented 5 certain new and useful Improvements in Metal Walls for Buildings, Masonry-Work, and the Like, of which the following is a specification.

The present invention relates to an improved metal wall by means of which transmission of heat is efficiently prevented.

The improved wall may be employed in all descriptions of buildings, masonry work and the like.

15 The invention is shown in the accompanying drawings in which

Figure 1 is a front view of my improved metal wall, and Fig. 2 is a section on line $x-x$, Fig. 1.

20 The wall comprises steel or iron tees a which serve as pillars or uprights. Between adjacent tees are arranged steel or iron sheets, each consisting of a front portion $d e$ and a pair of flanges $d c$ and $e f$ projecting rearwardly from the outer ends of the front portion and at right angles thereto. The flange $e f$ has an inturned end $f g$ at right angles to the flange and the flange $d c$ has a similar end $b c$. The sheets are secured to the tees a by 25 means of bolts or rivets h passing through the shank of the tees and through the flanges of the sheet. Within each sheet is arranged a plate i of magnesite, cork, waste conglomerate or other non-conducting material and upright wooden posts l are inserted between 35 the plate i and the front portion $e d$ of the metal sheet to hold the plates against the inturned ends $f g$ and $b c$ and to provide an air chamber k between the plates and the front portion of the sheets. 40

Having described my invention, what I claim as new is:

1. A metal wall comprising uprights, a metal sheet secured to said uprights and having flanges provided with an inturned end, a 45 plate of nonconducting material seated within the flanges of the sheet, and posts inserted between the plate and the main portion of the sheet and holding the sheet against the inturned ends of the plate to provide an air 50 chamber between the plate and the sheet.

2. A metal wall adapted to prevent the transmission of heat, consisting of uprights of tee iron, a metal sheet bent in $\square$ form at its edges and secured to the uprights, a plate 55 of non conducting material seated within the edges of the sheet, and posts inserted between the plate and sheet to provide an air chamber between the plate and the sheet.

This specification signed and witnessed 60 this twenty fifth day of April, 1906.

JOHN PETERS.
